TREATMENT OF HYDROCARBON OILS

Filed Oct. 28, 1932

UNITED STATES PATENT OFFICE

2,001,910

TREATMENT OF HYDROCARBON OILS

Vladimir Ipatieff, Chicago, Ill., assignor to Universal Oil Products Company, Chicago, Ill., a corporation of Delaware

Application October 28, 1932, Serial No. 649,123

6 Claims. (Cl. 196—10)

This invention relates to the treatment of hydrocarbon oils and refers more particularly to the treatment of the low boiling naphthas and gasolines produced from crude petroleums by fractionation under conditions involving substantially no cracking.

In a more specific sense the invention has reference to a process for treating said "straight run" gasolines to improve their quality with respect to gum and color-forming compounds present and in a specific sense in regard to improving their antiknock value and increasing their yield. The details of the process whereby these desirable refining effects are accomplished are given in the following specification.

In a general way the gasoline fractions present in crude petroleums and which may be removed therefrom by fractionation at moderate temperatures and pressures reflect the character of the crude petroleum, i. e., they may vary with the type of crude in the proportions of such hydrocarbon groups as paraffins, olefins, naphthenes, aromatics and the sulphur and nitrogen compounds which may be present. Although there are cases of considerable divergence from this rule, it has been repeatedly noted that the gasolines from paraffinic crudes such as those from the Pennsylvania and some of the Mid-Continent fields are highly paraffinic and highly knocking in character. The gasolines from the Mid-Continent field crudes and some of the Gulf crudes have an intermediate character in respect to antiknock value, indicating possibly the presence of relatively higher percentages of cyclic compounds of the nature of naphthenes or of isoparaffins. Certain crude oils from the Pacific Coast producing areas and some Texas fields yield gasolines of comparatively high antiknock value, owing to the cyclic character of the crude oils. These observations as to the variable character of straight run gasolines are merely adduced in a general way to show that different gasolines or naphthas may require different degrees of treatment according to the process of the invention to be presently disclosed in order to render them up to the prevailing market standards for antiknock value.

The present invention comprises a process of treatment whereby the character of the hydrocarbons present in straight run gasolines is altered in the direction of increased antiknock value.

The process furthermore effects a conservation of some of the waste products of cracking processes which are caused to combine chemically with certain hydrocarbon groups in straight run gasolines so that the overall yield of product is increased by this synthetic step.

In one specific embodiment the invention comprises treatment of hydrocarbon mixtures of the

character of straight run gasolines with olefins in the presence of sludge sulphuric acid to produce hydrocarbons which add antiknock value to the gasoline and at the same time to produce other desirable treating effects.

The term "olefin" as used within the concept of the present invention comprises any compound of carbon and hydrogen of open chain structure and containing one or more double bonds between carbon atoms. The following tabulation gives a few of the lower boiling members of the ethylene series which consists of homologs of the base substance ethylene containing one double bond:

Table No. 1

		15
Ethylene.	$\text{CH}_2=\text{CH}_2$.	-102.7°
Propylene.	$\text{CH}_3\text{CH}=\text{CH}_2$.	-48° gaseous
		-5°
Ethyl ethylene (n-butylene).	$\text{CH}_3\text{CH}_2\text{CH}=\text{CH}_2$.	20
Plane-sym. dimethyl ethylene.	$\text{CH}_3\text{CH}=\text{CH}_2\text{CH}_3$.	+1°
Axial-sym. (iso-butylene).	$(\text{CH}_3)_2\text{C}=\text{CH}_2$.	+2.5°
Unsym. dimethylene (iso-butylene).	$\text{CH}_3\text{CH}_2\text{CH}_2\text{CH}=\text{CH}_2$.	-6°
n-propyl ethylene (alpha-amylylene).	$(\text{CH}_3)_3\text{CH}=\text{CH}_2$.	25
Isopropyl ethylene (alpha-isoamylylene).	$(\text{CH}_3)_2\text{CH}=\text{CH}_2$.	+21°
Sym. methyl ethyl ethylene (beta-amylylene).	$\text{CH}_3\text{CH}_2\text{CH}=\text{CH}_2\text{CH}_3$.	+36°
Unsym. methyl ethyl ethylene (gamma-amylylene).	$\text{CH}_3\text{CH}_2\text{CH}=\text{CH}_2$.	30
Trimethyl ethylene.	$(\text{CH}_3)_3\text{C}=\text{CH}_2$.	+36°
Tetramethyl ethylene.	$(\text{CH}_3)_4\text{C}=\text{C}(\text{CH}_3)_2$.	+73°

Beginning with compounds of four carbon atoms, the table shows that a number of isomers are possible corresponding to different positions of the double bond and the presence of tertiary or quaternary carbon atoms, the number of possible isomers increasing as the number of carbon atoms increases. From these considerations it is evident that for the ethylene series alone a large number of different olefins may be employed either singly or in admixture for condensation with paraffin hydrocarbons according to the process of the invention.

The invention may further comprise the utilization of open chain unsaturated hydrocarbons of the acetylene or the diolefin series comprising such compounds as acetylene, butadiene, etc., and their homologs. While pure compounds of this character and even ethylene itself do not react readily even with aromatics in the presence of sulphuric acid catalyst there is apparently some alkylation by these compounds when used in admixture with other olefins as occurs in the case of gases from cracking plants.

The reactions involved in treatments according to the process of the invention are of considerable complexity owing to the large number of hydrocarbon types represented in the gasolines

treated on the one hand and the large number of olefins which may be employed on the other hand to alter the character of the gasoline. Merely to exemplify to some extent the character of the reactions which may occur, those which take place when a single olefin such as propylene is caused to join with benzol to produce an alkylated derivative may be considered. When gaseous propylene is passed into a well-stirred mixture of benzol and concentrated sulphuric acid in proper proportions, the propylene is apparently sulfonated at first to produce a monopropylsulfuric acid, and there are indications that the benzol may be sulfonated to some extent. The sulphuric acid derivatives then react to form a propylated benzol and regenerate to a large extent the sulphuric acid so that the net result of the reactions is expressed by the following equations which show the formation of mono- and di-isopropyl benzol:

5
10
15

6-14 (C-3417/2)

25 The relative proportions of the mono- and di-derivatives will depend upon such factors as the relative proportions of the two hydrocarbons employed, the rate of introduction of the propylene into the acid-aromatic mixture, the strength
30 of the acid and particularly the temperature which in the majority of cases of this character is best maintained at at least atmospheric temperature to minimize loss of olefins by polymerization. In the above reactions propylene represents
35 any of the homologs of ethylene, although ethylene itself is not specially reactive. Similarly benzol represents any of the aromatic series of hydrocarbons and may also typify the polynuclear aromatics such as naphthalene and anthracene.
40 However, the proportion of these polynuclear aromatics is undoubtedly very small in straight run gasoline fractions which commonly boil under 437° F.

45 The reactions given above in connection with olefins and aromatics are obvious and readily understandable to those versed in organic chemistry. However, it is advanced as a particular feature of the present invention that unusual and unexpected results have been obtained when 50 treating gasolines with olefins and olefin mixtures in the presence of sulphuric acid when the gasolines are of a paraffinic character as produced from Pennsylvania crude oils and contain substantially no hydrocarbons of a distinctly 55 aromatic character though possibly a considerable percentage of naphthenes. Owing to the difficulties of exact analysis in the case of hydrocarbon oil mixtures only a limited amount of data is available on the subject of the proximate composition 60 of gasolines, but considerable qualitative and some semi-quantitative experiments have indicated that the so-called paraffinic gasolines may consist not only of normal or straight chain paraffins but also to a large extent of so-called iso 65 or branched chain paraffins and cyclic compounds of a saturated or partially saturated character such as the naphthenes and mixed alkyl derivatives thereof. The course of the reactions which lead to the improvements noted in the case of 70 straight run paraffinic gasolines when treated by the process of the present invention may consist in rearrangements among the substituting groups either in the open chain or closed chain hydrocarbons, or it may comprise the direct addition of 75 olefins to central carbon atoms in the paraffinic

chains. Such reactions cannot be closely followed owing to the difficulties in securing reliable analytical data.

The following equations in addition to those previously given suggest further reactions which may take place when olefins are contacted with straight run gasolines in the presence of sulphuric acid under regulated conditions. In the case of a straight chain paraffin such as pentane, the following equation expresses a possible reaction:

Owing to the observed increase in antiknock value which occurs many times in the alkylation of straight run gasolines according to the process of the invention it is probable that at least some of the methyl or other alkyl groups attach to the carbon chain in a central position so that iso-compounds are formed, since it is known that hydrocarbons of higher antiknock value are obtained when the carbon atoms are arranged more compactly.

The equation given below suggests a reaction which might be presumed to take place between an olefin and a naphthalene or a partially hydrogenated aromatic of a mixed or terpene-like character:

The foregoing suggested reactions merely indicate possible trends and many other and more complicated reactions may occur owing to the possibility of the shifting of labile hydrogen atoms and alkyl groups such as methyl, ethyl, propyl, etc.

A feature of the present invention is that sludge acids resulting from the treatment of petroleum products, cracked distillates, gases from a cracking process and other products containing olefins and aromatic hydrocarbons and the like, is employed as a catalyst and/or polymerizing agent in the process. When sulphuric acid is used to catalyze reactions of the general character just described as occurring between olefins and other classes of hydrocarbons its strength must be carefully controlled and the temperature at which the reactions are conducted must be held below a certain point if best results are to be secured in the production of yields of products of the desired boiling range and quality. For example, in the reactions between propylene and benzol just described best results are obtained if the temperature is maintained in the neighborhood of 0° C. When conditions are such that the reactions leading to the formation of alkyl derivatives of hydrocarbons predominate, it would appear that the initial stage of the reactions corresponds to the formation of sulphuric acid esters of olefins and in compounds corresponding to sulfonic acids of benzol, which further react to form the alkylated hydrocarbon and regenerate the sulphuric acid. When sulphuric acid over a certain limit strength is employed, temperatures are allowed to rise, or there is a lack of intimate contact between the reacting constituents, there is an increased tendency toward the formation of polymers of the olefins. This is particularly noticeable in employing olefinic hydrocarbons which occur in gases from cracking processes since there are numerous types of olefins of highly unsaturated character present whose polymers are of a gummy or tarry character and

hence undesirable in the alkylated product which is primarily intended for use as a blending material to improve the antiknock characteristics of motor fuel. Furthermore, unless conditions are kept within narrow limits, there is a tendency for the formation of highly alkylated hydrocarbons which may contain, for example, three or four substituting groups and which are of too high boiling character to be used in gasoline without unduly increasing its end boiling point.

It has been found that if sludge acids are employed in place of fresh acid that the conditions of operation in alkylating hydrocarbons to produce gasoline boiling range compounds admit of considerably greater latitude. There is less tendency toward the formation of gummy polymers or too highly alkylated compounds and owing to the more selective and moderate nature of the reactions there is a decreased tendency toward excessive temperature rise due to heat of reaction, and proper conditions of treatment are more easily maintained in practice.

The term "sludge acid" as used in the present specification may refer to any of the partly spent acids used in conducting treatments upon any of the miscellaneous oils treated in connection with the refining of petroleum, and it also includes in its meaning sludges which may be produced in alkylating hydrocarbons with olefins where fresh acid was employed, the last named class being in a sense recirculated acid. In other words the invention comprises the use of sludges resulting from the sulphuric acid treatment of such miscellaneous oils as gasolines, both cracked and straight run, naphthas, kerosenes, lubricating oils, etc. Since the object in using sludge acid is to catalyze the desired reactions by acids diluted by soluble organic products rather than by water, it is also comprised within the scope of the invention to synthetically produce a sludge acid of desired characteristics by properly blending a sludge acid with fresh or unused sulphuric acid to produce a reagent of the desired activity. Obviously this procedure admits of the production of a large number of reagents of properties varying generally with the percentage and strength of free sulphuric acid present and while a number of alternatives are possible it is to be understood that they are not necessarily equivalent in their action.

The process of the invention is advantageously employed in connection with the utilization of the olefins in the gases produced as a by-product of oil cracking processes whose primary object is the production of gasoline. The amount of gas produced in such processes varies generally with the intensity of cracking conditions and the olefinic content of such gases is frequently very high, sometimes running 40 to 50% by volume in the case of gases produced in high temperature-low pressure vapor phase cracking processes. Such gases contain large amounts of ethylene, propylene, butylenes, and amylenes though usually propylene predominates, this particular olefin frequently constituting as high as 30% of the total gas mixture.

According to the process of the invention individual olefins or mixtures of olefins and other hydrocarbon gases such as those present in gases from oil cracking processes are contacted with reactive hydrocarbons in the presence of sludge acid. While the process is not limited to the use of any particular type of apparatus or plant arrangement it will assist in defining its character to describe an operation in connection with

one arrangement of inter-connected elements which may be employed and for this purpose the attached drawing is provided which shows diagrammatically and without reference to any particular scale, an arrangement of apparatus which may be employed.

Referring to the drawing, the essential features of the plant shown are seen to be a source of supply for olefin-containing gas, aromatic liquid and sludge acid, chambers in which the gas and liquids are reacted in the presence of the acid, settlers for separating the alkylated product from partly spent acids and neutralizing and washing tanks. The last named are not a special feature of the process as the neutralizing and washing of products from acid-treatments is well established in the art and, furthermore, the layout shown provides no means for redistilling the purified product though this may be done if and when necessary. Obviously the exact type of mixer for liquid hydrocarbon, acid and gas will be modified to obtain best results in any given case and the details of construction may be altered in accordance with special needs. However, the operation to be described is sufficiently illustrative.

In the drawing shown an olefin-containing gas such as the mixture produced from an oil cracking process is introduced to the system through a line 1 containing control valve 2, line 1 having a branch line 3 containing control valve 4. It is assumed for the purposes of the present discussion that the gas is under sufficient pressure as it comes from a cracking plant so that pumping means are not necessary. An inlet gas pressure of about 100 pounds may be desirable in processes of the present character as there is considerable differential encountered in the flow through the apparatus and the reactions are further assisted by pressure as will be later developed. In the present set-up, line 3 conducts the gas to a primary reactor 5 while line 1 serves to conduct it to a secondary reactor 6. The reactors are provided with sprays 55 and 58 respectively and also superimposed perforated plates 56, 57, 59 and 60 as shown to break up the oil and acid into a fine spray or mist which is thus brought into intimate contact with the gas, the reaction taking place with all constituents flowing downwardly.

In the arrangement shown the order of the reactors may be reversed, since the acid, gas and oil lines are manifolded but for purposes of the present description reactor 5 will be considered as the primary reactor in which the inlet gas rich in olefins is contacted with fresh hydrocarbon liquid in the presence of partly spent acid, while the residual gas from this primary operation is contacted with separate portions of hydrocarbon liquid in secondary reactor 6 in the presence of stronger acid. The concurrently principle of treatment, which is shown as a feature of the process in connection with the drawing, while a convenient and efficient mode of operation, is not an essential feature of the present invention, which may comprise operations of a once-through or batch character. The principle of concurrently treatment in connection with the present process may be applied in still other ways than that shown, since there are three separate substances participating in the general reactions, to wit, olefin-containing gases, hydrocarbon liquid and sulphuric acid. To enumerate some of the possible combinations it may be stated that (1) gases and hydrocarbon liquids may be di-

- rected counter-current to acid, (2) acid and hydrocarbon liquids may be directed counter-current to gases and (3) acid and gases may be directed counter-current to hydrocarbon liquid.
- 5 Any of these particular operations are comprised within the scope of the invention and may be utilized at particular times although for purposes of clarity the description of an operation in which acid is passed concurrently of hydrocarbon liquids and gases is generally adhered to.
- 10 The incoming gas is thus introduced to reactor 5 through line 3 while fresh hydrocarbon liquid mixed with sludge acid is introduced from line 14. All supply tanks and receivers are shown in duplicate arrangement to assist in assuring continuous operation of the process. Thus hydrocarbon liquid may be taken by pump 13 from supply tanks 7 or 8 either through line 9 containing control valve 10 or line 11 containing control valve 12 and discharged through line 14 containing control valves 15 and 16 into reactor 5 as shown. Line 17 containing control valve 18 provides for the introduction of the hydrocarbon liquid into secondary reactor 6. Sludge acid from the reactions in the primary reactor 5 may be taken from either receiver 31 or 32 through line 33 containing control valve 34 or line 35 containing control valve 36 respectively and pumped by pump 37 through line 38 containing control valve 39 to line 41 containing control valve 42 and thence to line 14 and spray 55. The sludge acid catalyst may be continuously circulated to insure its maximum utilization and when its effectiveness is reduced below an economical point by the gradual accumulation of soluble esters, etc., a portion of it may be continuously or intermittently discharged through branch line 38' containing valve 39' and the necessary amount of make-up acid, either fresh or sludge, introduced from the primary sludge acid supply. If desired or if advantages are gained thereby, partly spent acid from the reactions in the secondary reactor 6, obtained from tanks 43 and 44, may be recycled to the primary reactor 5, valve 54 being entirely 40 or partially closed and valve 52 being open at such times. In ordinary operations the sludge product from the secondary reactor will be circulated by way of line 53 containing control valve 54, line 26 and line 17 until its efficiency drops below an economical point.
- 45 To reduce polymerization and undesirable side reactions the products from the reactor are discharged in toto through a cooling coil prior to their separation into a sludge acid layer, alkylated liquid and unreacted gases. Thus a header 61 contains valves 62, 62', 63 and 63' and permits the utilization of cooling coils 64, 65 and 66 as may be found most expedient. Similarly a header 67 may receive cooled products from any one 50 of the three coolers and direct the cooled products to either one of settling tanks 70 and 73 by the proper manipulation of valves 68 and 69.
- 55 In settling tank 70 gas, hydrocarbon liquid and sludge acid from the primary reactor separate, the gas being released through line 76 containing control valve 77 to line 1 leading to secondary reactor 6. The liquid product shown as layer 78 may as desired be recirculated to the primary reactor, further treated in the secondary reactor or withdrawn from the process for neutralizing and washing as a final product. In the first case a pump 90 may withdraw the liquid layer through line 88 containing a control valve 89 and return the partially alkylated liquid to 60 the primary reactor by way of line 91 and valve 92, line 91' and valve 92' and line 14. When the partially alkylated liquid products from the reactor are to be treated in the secondary reactor, valve 92' is closed and the liquid proceeds to the secondary reactor by way of lines 26 and 17. In the event that further alkylation is not desired the liquid product may be diverted into line 93 containing control valve 94 and thus through line 95 containing control valve 96 (which serves a similar purpose for the corresponding material in settling tank 73) into neutralizing tank 97 to be later described.
- 65 Partly spent acid from settling tank 70 shown as layer 72 may be drawn to intermediate accumulators 31 and 32 through line 80 containing control valve 81 or line 82 containing control valve 83 respectively as may be expedient. When the sludge from this stage is to be further used, pump 37 is used for recirculating the first stage sludge acid into reactor 5, the stream being diverted through line 41 containing control valve 42, valve 40 being closed.
- 70 In secondary reactor 6 according to the flow at present being described fresh or partly alkylated hydrocarbon liquid is contacted with the olefin-containing gas from the first reactor in the presence of sludge acid of relatively greater activity. The main advantage gained by this operation is that more acid may be used and a higher rate of alkylation effected without increased tendency toward polymerization among the olefins, since these no longer comprise the more readily reactive members which were lost in the primary reactor. Thus sludge acid from a source outside the process may be taken from supply tanks 19 or 20 through line 21 containing control valve 22 or line 23 containing control valve 24 respectively and pumped by pump 25 through line 26 containing control valves 27 and 28 into secondary reactor 6. The products of this second stage in respect to the gas or the primary stage in respect to the acid may then be discharged through a cooler selected from those already described and passed to a settling tank, in the present instance settling tank 73 which shows again alkylated hydrocarbon liquid as layer 74 and sludge acid as layer 75. The gas from this stage, being now substantially free from reactive olefins, is vented through line 78 containing control valve 79 and may be put to any use for which it is suited.
- 75 The sludge acid from the second stage is drawn from settling tank 73 to tanks 43 and 44 through lines 84 containing control valve 85 or line 86 containing control valve 87 and may be further used in either of the reactors as its strength may indicate, though in the preferred mode of operation it will be used in the primary reactor 5 for reasons which have been already given. Thus pump 49 may withdraw this acid from tank 43 through line 45 containing control valve 46 or from tank 44 through line 47 containing control valve 48 and discharge it through line 50 containing control valves 51 and 52. When this sludge acid is to be used in primary reactor 5, valves 51 and 52 will be open and the acid will pass directly to line 14. If used for any reasons in secondary reactor 6 it may be diverted through branch line 53 containing control valve 54 and ultimately reach the reaction zone through line 70 71. Line 50' containing valve 51' is provided to permit the discharge from the system of the spent acid resulting from the reactions in the secondary reactor, the make-up acid being introduced from a fresh supply or the primary sup- 75

ply consisting of sludge having a relatively high sulphuric acid concentration.

- The alkylated hydrocarbons from settling tank 73 may be passed to the neutralizing tank through line 95 containing control valve 96 either alone or in admixture with analogous products from settling tank 70 as previously described. Caustic soda of any desired strength may be taken from tanks 98 and 99 through line 100 containing control valve 101 or line 102 containing control valve 103 and pumped by a suitable pump 104 through line 105 containing control valve 106 from which it is allowed to pass downwardly counterflow to the ascending alkylated products. The neutralizing tank is preferably so designed that the rates of oil and alkali can be adjusted and a substantially neutral or slightly alkaline liquid may be recovered from the top of the tank, this liquid passing through line 111 containing control valve 112 into a water washing tank 113. To provide for the removal of any accumulation of gases a vent line 126 containing control valve 127 is provided in the top of the neutralizer. Line 107 containing control valve 108 permits the removal of spent neutralizing liquor. Line 109 containing control valve 110 is provided to permit the recirculation of a portion or all of the caustic solution as long as it retains sufficient neutralizing power.

- In the water washing tank the same counter-flow methods may be employed, water being introduced through a line 114 containing control valve 115 in the form of a spray and the washed product drawn from the top of the tank through a line 118 containing control valve 119 and passing either to final receiver 124 through line 120 containing control valve 121 or to receive 125 through line 122 containing control valve 123.

A commercial application of the process of the invention is well exemplified in the treatment of a straight run gasoline with the gases from a cracking process. In such operations several modes of procedure will present themselves to those conversant with commercial practices.

In the simplest case a selected sludge containing approximately 75% sulphuric acid equivalent may be stirred into a stationary body of gasoline in a batch agitator and a stream of olefin-containing gases bubbled through the suspension through a spray or other distributing means. It is usually preferable to have cooling coils immersed in the reaction mixture so that excessive temperature rise is avoided.

The example involves the treatment of a Pennsylvania straight run gasoline with the gases produced in cracking a fuel oil distillate from the same crude. The gasoline before treatment may have the following properties:

60 Gravity ° A. P. I.	65.0	
Initial boiling point ° F.	100	
10% over at	152	
20% over at	180	
30% over at	200	
40% over at	217	
50% over at	234	
60% over at	250	
70% over at	265	
80% over at	288	
90% over at	322	
End point (97.5%)	380	

When a blend of 90 parts of a test gasoline showing 67.5 octane number and 10 parts of this gasoline is tested, an antiknock value of 52 octane number is obtained.

This gasoline may be treated with an olefinic gas mixture containing approximately 35% propylene by volume, this gas being produced in conjunction with cracking the fuel oil distillate to produce gasoline. In the run 5.5 gals. of the straight run gasoline, 4.0 gals. of sludge acid and 1860 cu. ft. of the gas per hour may be injected into a mixing box at the top of a tower through which the injected materials pass downwardly. As a result a volume of 235% of alkylated hydrocarbons may be produced based on the volume of the original gasoline. The properties of the alkylated product may be as follows:

Gravity ° A. P. I.	55.0	15
Initial boiling point ° F.	90	
10% over at	175° F.	
20% over at	208	
30% over at	236	
40% over at	256	
50% over at	296	20
60% over at	342	
70% over at	395	
80% over at	485	
End boiling point (85%)	540	25

When this product is again used in 10% blend with the reference fuel of 67.5 octane number, the blend may test 83 octane number which indicates the remarkable improvement effected by the treatment since the average boiling point of the product is considerably higher than the original gasoline and yet the antiknock value is much higher as shown by comparing the octane numbers.

The blending fluid thus produced may be distilled after a caustic wash with no change in color or odor or the development of sulphur compounds due to decomposition of soluble acid esters.

The foregoing specification has described and disclosed the general and broad character of the invention and the example is sufficiently indicative of its value from a commercial standpoint. However, the invention is not limited in scope to the exact details of the descriptive material or the experimental data given.

I claim as my invention:

1. A process for the treatment of straight run distillate containing gasoline hydrocarbons to produce high anti-knock motor fuels therefrom and to increase the volume thereof suitable for high anti-knock motor fuels, which comprises simultaneously subjecting said straight run distillate and gases resulting from a cracking process to the action of preformed sludge acid derived from the treatment of hydrocarbons with sulphuric acid, reacting components of the distillate with olefins contained in the gases to form alkylated derivatives, and recovering the resulting liquid product.

2. A process for the treatment of straight run distillate containing gasoline hydrocarbons to produce high anti-knock motor fuels therefrom and to increase the volume thereof suitable for high anti-knock motor fuels, which comprises simultaneously subjecting said straight run distillate and gases containing olefin hydrocarbons to the action of preformed sludge acid derived from the treatment of hydrocarbons with sulphuric acid, reacting components of the distillate with olefins contained in the gases to form alkylated derivatives, and recovering the resulting liquid product.

3. A process for the treatment of straight run distillate containing gasoline hydrocarbons to

produce high anti-knock motor fuels therefrom and to increase the volume thereof suitable for high anti-knock motor fuels, which comprises simultaneously subjecting said straight run distillate and gases resulting from a cracking process to the action of preformed sludge acid derived from the treatment of cracked hydrocarbon oil with sulphuric acid, reacting components of the distillate with olefins contained in the gases to form alkylated derivatives, and recovering the resulting liquid product.

4. A process for the treatment of straight run distillate containing gasoline hydrocarbons to produce high anti-knock motor fuels therefrom and to increase the volume thereof suitable for high anti-knock motor fuels, which comprises simultaneously subjecting said straight run distillate and gases resulting from a cracking process to the action of preformed sludge acid derived from the treatment of cracked gases with sulphuric acid, reacting components of the distillate with olefins contained in the gases to form

alkylated derivatives, and recovering the resulting liquid product.

5. A process for increasing the anti-knock value of light distillates containing a substantial quantity of hydrocarbons within the gasoline boiling range, which comprises forming alkylated compounds in the ristillate by reacting components of the latter with olefins in the presence of preformed sludge acid derived from the treatment of hydrocarbons with sulphuric acid.

5

6. A process for increasing the anti-knock value of light distillates containing a substantial quantity of hydrocarbons within the gasoline boiling range, which comprises treating the distillate with olefinic gas in the presence of preformed sludge acid derived from the treatment of hydrocarbons with sulphuric acid, reacting components of the distillate with olefins contained in the gas to form alkylated derivatives, and recovering the distillate containing the derivatives thus formed.
